(57) **ABSTRACT**

Described herein is a process for the preparation of a mixture of compounds of formula

having a weight ratio of the cis-diastereomers to trans-diastereoisomers higher than 1:1, where R₁ represents a C₁₋₈ alkyl group, a C₂₋₈ alkenyl group or a C₂₋₈ alkynyl group, each optionally substituted with one or two of a C₁₋₄ alkyl alkoxy ether group and/or a C₁₋₄ alkyl carboxylester group and R₂ represents a C₁₋₆ alkyl, a C₂₋₆ alkenyl or a C₂₋₆ alkynyl group, each optionally substituted with a C₁₋₄ alkyl alkoxy ether group, a carboxylic acid group or a C₁₋₄ alkyl carboxylester group and compounds suitable in the process.

**CROSS-REFERENCE TO RELATED
APPLICATIONS**

This application is a *reissue application of U.S. Pat. No. 11,339,113 B2, which was filed as U.S. patent application Ser. No. 17/273,357 on Mar. 4, 2021, and issued on May 24, 2022, which was filed as a U.S. National Phase Application of International Patent Application No. PCT/EP2019/085416, filed Dec. 16, 2019, which claims the benefit of priority to European Patent Application No. 18214113.5, filed Dec. 19, 2018, the entire contents of which are hereby incorporated by reference herein.*

TECHNICAL FIELD

The present invention relates to the field of organic synthesis. More particularly, it provides a process for the preparation of a mixture of compounds of formula (I) having a weight ratio of the cis-diastereomers to trans-diastereomers higher than 1:1 and compounds suitable in said process.

BACKGROUND

The compounds of formula (I), as defined in more detail below, can be generally useful as perfuming ingredients or as building blocks in the perfume industry. The mixtures of cis-diastereomers and trans-diastereomers of compounds of formula (I) can also have certain beneficial olfactory effects.

The methods of preparation of said compounds and mixtures of said compounds reported in the prior art, such as in U.S. Pat. No. 5,728,866, EP1900720 or Eur. J. Org. Chem. 2001, 3837, are generally long and expensive. It is therefore highly desirable to access said compounds and mixtures of said compounds by using a simple and efficient process of preparation wherein the starting material is an easily accessible material.

To the best of our knowledge, the prior art did not disclose or suggest the process of preparation according to the present invention providing a direct access to compounds or mixtures of compounds of formula (I).

DESCRIPTION OF THE INVENTION

In order to solve the aforementioned problem, the present invention provides a process for the preparation of a mixture 55 of compounds of formula (I).

(I)

having a weight ratio of the cis-diastereomers to trans-diastereomers higher than 1:1,

wherein R₁ represents a C₁₋₈ alkyl group, a C₂₋₈ alkenyl group or a C₂₋₈ alkynyl group, each optionally substituted with one or two of a C₁₋₄ alkyl alkoxy ether group and/or C₁₋₄ alkyl carboxylester group, and R₂ represents a C₁₋₆ alkyl group, a C₂₋₆ alkenyl group or a C₂₋₆ alkynyl group, each optionally substituted with an C₁₋₄ alkyl alkoxy ether group, a carboxylic acid group or a C₁₋₄ alkyl carboxylester group,

by subjecting a mixture comprising compounds of formula

25 having a weight ratio of the cis-diastereomers to trans-diastereomers equal or lower than 1:1,

wherein R₁ and R₂ have the same meaning as indicated above,

30 to the steps comprising (a) ketal formation, (b) separating the trans-diastereomers and cis-diastereomers and (c) hydrolyzing the ketal of the cis-diastereomers.

35 By the terms "cis-diastereomer" and "trans-diastereomer", it is understood the normal meaning of said terms to the person skilled in the art. In the context of the present invention, the terms "cis-diastereomer" and "trans-diastereomer" mean the relative configuration of the substituent R₁ to the substituent R₂. The term "cis-diastereomer" means 40 that the substituents R₁ and R₂ are sterically directed in the same direction relative to the cyclopentane ring whereas the term "trans-diastereomer" means that the substituents R₁ and R₂ are sterically directed in different directions relative to the cyclopentane ring. Thus, the compounds of formula (I) 45 comprise two cis-diastereomers having the absolute configuration according to formula

50 55 60 65 66 and two trans-diastereomers having the absolute configuration according to formula

(III)

linear C_{3-7} alkynyl group and R_2 represents a C_{1-3} alkyl group substituted with a C_{1-3} alkyl carboxylester group.

According to any embodiments of the invention, the compound of formula (I) is defined in that R_1 represents a linear C_{4-6} alkyl group or a linear C_{3-7} alkenyl group or a linear C_{3-7} alkynyl group and R_2 represents a C_{1-3} alkyl group substituted with a C_{1-3} alkyl carboxylester group.

According to any embodiments of the invention, the compound of formula (I) is methyl-3-oxo-2-pentylcyclopentanacetate, methyl-3-oxo-2-(2-pentenyl)-1-cyclopentaneacetate or (Z)-methyl-3-oxo-2-(2-pentenyl)-1-cyclopentaneacetate. Preferably, the compound of formula (I) is methyl-3-oxo-2-pentylcyclopentanacetate.

15 The first step of the inventive process is subjecting the starting mixture comprising compounds of formula (I) having a weight ratio of the cis-diastereomers to trans-diastereomers equal or lower than 1:1 to the step of ketal formation, preferably to the step of cyclic ketal formation. Thereby 20 it is understood that the compound of formula (I) is subjected to reaction conditions which form a ketal function. A skilled person is aware of several methods to prepare a ketal.

According to a particular embodiment, the weight ratio of the cis-diastereomers to the trans-diastereomers of the starting 25 mixture is less than 40:60, more preferably less than 30:70, more preferably less than 20:80, more preferably less than 15:85 and even more preferably less than 10:90.

Typically, a ketal can be formed by subjecting a ketone, such as the compound of formula (I), to an alkyl monoalcohol, such as C_{1-3} alkyl mono alcohol, or an alkyl diol, such as defined below, in the presence of a catalyst.

According to a particular embodiment, the ketal formation according to step (a) is carried out in the presence of a catalyst being an acid, preferably H_2SO_4 , pyridium tosylate, 35 $MHSO_4$ wherein M is an alkaline metal, such as sodium or potassium, $Al_2(SO_4)_3$, heterogeneous solid acid, such as resin acid (e.g. Amberlyst), zeolite or clay, alkyl or aryl sulfonic acid, such as methylsulfonic acid or para-toluone-sulfonic acid, more preferably $KHSO_4$.

40 The amount in which the catalyst, preferably the acid, may be employed in the ketal formation step is typically comprised between 0.01 and 10 mol %, relative to the weight of the substrate. In a preferred embodiment, the catalyst, preferably the acid, is used in a concentration 45 comprised between 0.1 to 5 mol %.

According to a particular embodiment, the ketal formation according to step (a) is carried out in the presence of a C_{1-3} alkyl mono alcohol, such as $MeOH$ or $EtOH$, or an alkyl diol of formula $HO—C(R_4)H—(C(R_4)_2)_n—H(R_4)C—OH$ 50 wherein n is an integer from 0 to 3 and R_4 , each independently, is a hydrogen or C_{1-3} alkyl group, preferably in the presence of an alkyl diol of formula $HO—C(R_4)H—(C(R_4)_2)_n—H(R_4)C—OH$.

According to a particular embodiment, the ketal formation 55 according to step (a) is carried out in the presence of ethylene glycol, 1,3-propanediol, 2,3-butanediol, 1,2-propanediol, 2,2-dimethyl-1,3-propanediol, 1,2-butanediol, 2-methyl-1,3-propanediol, preferably ethylene glycol, 1,3-propanediol, 2,2-dimethyl-1,3-propanediol, even more preferably ethylene glycol. In other words, the step (a) of the invention process may be a cyclic ketal formation.

The ketal formation according to step (a) may be carried out in the presence or absence of a solvent. When a solvent is required or used for practical reasons, then any solvent current in such reaction type can be used for the purposes of the invention. Particularly, the ketal formation according to step (a) may be carried out in a hydrocarbon solvent,

By the expression “weight ratio of the cis-diastereomers to trans-diastereomers higher than 1:1” of the prepared mixture, it is understood that the prepared mixture comprises more than 50% by weight of cis-diastereomers in comparison to less than 50% by weight of trans-diastereomers. According to a preferred embodiment, the weight ratio of cis-diastereomers to trans-diastereomers of the prepared mixture is at least 60:40, more preferably at least 70:30, more preferably at least 80:20 and even more preferably at least 85:15.

The weight ratio of the cis-diastereomers to trans-diastereomers can be determined by GC. Typically, the peaks of the corresponding cis-diastereomers or trans-diastereomers are determined by GC and the corresponding peak area is integrated and compared with each other.

By the terms “alkyl”, “alkenyl” and “alkynyl”, it is understood the normal meaning of the terms to the person skilled in the art. Alkyl, alkenyl and alkynyl are understood as comprising linear and branched alkyl, alkenyl or alkynyl groups. The term “alkenyl” is understood as comprising 1, 2 or 3 olefinic double bonds, preferably 1 olefinic double bonds. The term “alkynyl” is understood as comprising 1, 2 or 3 triple bonds, preferably 1 olefinic double bonds.

By the terms “ C_{1-4} alkyl alkoxy ether group”, “carboxylic acid group” or “ C_{1-4} alkyl carboxylester group”, it is understood the normal meaning of the terms to the person skilled in the art. C_{1-4} alkyl alkoxy ether group is understood as a substituent being a C_{1-4} alkyl group substituted with a C_{1-4} alkoxy group. C_{1-4} alkyl carboxylester group is understood as a substituent being a carboxyl group with a C_{1-4} alkyl ester group; i.e. a $COOR$ group wherein R may represent a C_{1-4} alkyl group.

According to any embodiments of the invention, the compound of formula (I) is defined in that R_1 represents a linear C_{3-7} alkyl group or a linear C_{3-7} alkenyl group or a linear C_{3-7} alkynyl group, preferably a linear C_{4-6} alkyl group or a linear C_{4-6} alkenyl group, even more preferably a linear C_5 alkyl group or a linear C_5 alkenyl group.

According to any embodiments of the invention, the compound of formula (I) is defined in that R_2 represents a C_{1-3} alkyl group optionally substituted with a C_{1-3} alkyl carboxylester group, preferably a C_{1-2} alkyl group optionally substituted with a C_{1-3} alkyl carboxylester group, even more preferably, R_2 represents a methyl group, an ethyl group, a methyl acetate group (i.e. $CH_3C(O)OMe$), or an ethyl acetate group (i.e. $CH_3C(O)OEt$).

According to any embodiments of the invention, the compound of formula (I) is defined in that R_1 represents a linear C_{3-7} alkyl group or a linear C_{3-7} alkenyl group or a

preferably toluene, hexane, cyclohexane or heptane, more preferably toluene or heptane.

The temperature at which the ketal formation according to step (a) can be carried out is comprised between 60° C. and the refluxing temperature of the solvent, substrate or the alcohol. Preferably, the temperature is in the range of between 60° C. and 180° C., more preferably between 110° C. and 165° C. and even more preferably between 110° and 150° C. A person skilled in the art is also able to select the preferred temperature as a function of the melting and boiling point of the starting material and final products as well as of the solvent.

The second step of the inventive process is subjecting the mixture resulting from step (a) to the step of separating the trans-diastereomers and cis-diastereomers. A skilled person is aware of several methods of separating diastereomers. Typically such methods comprise column chromatography, distillation etc.

According to a particular embodiment, the separation according to step (b) is carried out by distillation, preferably by fractionated distillation.

The temperature at which the distillation can be carried out is comprised between 60° C. and 150° C., preferably between 100° C. and 130° C. A person skilled in the art is also able to select the preferred temperature as a function of the melting and boiling point of the starting material and final products.

The pressure at which the distillation can be carried out is at ambient pressure or under vacuum. Preferably, the pressure at which the distillation can be carried out is comprised between 0.1 mbar to 10 mbar.

The third step of the inventive process is subjecting the cis-diastereomer resulting from step (b) to the step of hydrolyzing the ketal of the cis-diastereomer.

According to a particular embodiment, the hydrolyzing according to step (b) is carried out in the presence of a hydrolyzing agent. A skilled person is aware of several methods to hydrolyze a ketal. Particularly, the hydrolysis may be performed in a presence of an acid. Said acid may be an acid being insoluble in aprotic and apolar solvents and soluble in water with solubility in water of at least 200 g L⁻¹. Said acid may process a pKa between 1 and 6.9. Said acid may be citric acid, malic acid, fumaric acid or tartric acid, preferably aqueous citric acid or tartric acid, even more preferably aqueous citric acid.

The amount in which the hydrolyzing agent, preferably the acid, may be employed in the hydrolyzing step is typically comprised between 0.1 and 50 mol %, relative to the weight of the substrate. In a preferred embodiment, the hydrolyzing agent, preferably the acid, is used in a concentration comprised between 5 to 30 mol %.

The hydrolyzing according to step (c) may be carried out in the presence or absence of a solvent. When a solvent is required or used for practical reasons, then any solvent current in such reaction type can be used for the purposes of the invention. Particularly, the hydrolyzing according to step (c) may be carried out neat or in heptane, preferably in heptane.

As an optional additional step, the cis-diastereomers resulting from step (c) can be subjected to a further purification step. A skilled person is aware of several methods of purifying diastereomers. Typically such methods comprise column chromatography, distillation etc. Preferably, the cis-diastereomers resulting from step (c) can be subjected to a further fractionated distillation, even more preferably flash fractionated distillation.

A further aspect of the present invention is a compound according to formula

wherein R₁ and R₂ have the same meaning as the compound according to formula (I), and R₃ represent, each independently, a C₂₋₃ alkyl group or, when two R₃ taken together, is a bivalent group —C(R₄)H—(C(R₄)₂)_n—H(R₄) C— wherein n is an integer from 0 to 3 and R₄, each independently, is a hydrogen or C₁₋₃ alkyl group, with the proviso that at least one R₄ is a linear or branched C₁₋₃ alkyl group when n is 0; provided that methyl 2-(3,3-diethoxy-2-propylcyclopentyl)acetate, methyl 2-(2-pentyl-3,3-dipropoxycyclopentyl)acetate, methyl 2-(2-ethyl-6-pentyl-1,4-dioxaspiro[4.4]nonan-7-yl)acetate, methyl 2-(1-pentyl-6,10-dioxaspiro[4.5]decan-2-yl)acetate, methyl 2-(7,9-dimethyl-1-pentyl-6,10-dioxaspiro[4.5]decan-2-yl)acetate, methyl 2-(3,3-diethoxy-2-heptylcyclopentyl)acetate and methyl 2-(3,3-diethoxy-2-hexylcyclopentyl)acetate are excluded.

The invention will now be described in further detail by way of the following examples, wherein the abbreviations have the usual meaning in the art, the temperature is indicated in degrees centigrade (C).

EXAMPLES

The invention will now be described in further detail by way of the following examples, wherein the abbreviations have the usual meaning in the art, the temperatures are indicated in degrees centigrade (° C.). NMR spectra were acquired using either a Bruker Avance II Ultrashield 400 plus operating at 400 MHz (¹H) and 100 MHz (¹³C) or a Bruker Avance III 500 operating at 500 MHz (¹H) and 125 MHz (¹³C) or a Bruker Avance III 600 cryoprobe operating at 600 MHz (¹H) and 150 MHz (¹³C). Spectra were internally referenced relative to tetramethyl silane 0.0 ppm. ¹H NMR signal shifts are expressed in S ppm, coupling constants (J) are expressed in Hz with the following multiplicities: s, singlet; d, doublet; t, triplet; q, quartet; m, multiplet; b, broad (indicating unresolved couplings) and were interpreted using Bruker Topspin software. ¹³C NMR data are expressed in chemical shift S ppm and hybridization from DEPT 90 and DEPT 135 experiments, C, quaternary, (s); CH, methine (d); CH₂, methylene (t); CH₃, methyl (q).

Example 1

The Inventive Process for Methyl-3-oxo-2-pentylcyclopantanacetate

1.1. Ketal Formation

Into a 1 L flask, equipped with a mechanical stirrer, a reflux condenser and a Dean Stark apparatus, 250 g of methyl-3-oxo-2-pentylcyclopantanacetate (96.2% purity), 400 g of toluene, 140 g of ethylene glycol and 2.3 g of potassium hydrogen sulfate were added. The resulting mix-

ture is brought to reflux during 10 h while removing water continuously by azeotropic distillation. The reaction is cooled to 50° C., subsequently neutralized by aqueous potassium carbonate and washed with water. After evaporation to dryness, 290 g of a crude material consisting of 20% methyl-3-oxo-2-pentylcyclopentanacetate, 67% trans-methyl-3-oxo-2-pentylcyclopentanacetate ethyleneglycol ketal and 10% cis-methyl-3-oxo-2-pentylcyclopentanacetate ethyleneglycol ketal were obtained.

1.2. Fractional Distillation

A fractional distillation of the crude material was conducted (T_{vap} 92-110° C./1 mbar).

3 main fractions were obtained.

Fraction 1: methyl-3-oxo-2-pentylcyclopentanacetate 43.6 g (97.5% purity)

Fraction 2: trans-methyl-3-oxo-2-pentylcyclopentanacetate ethyleneglycol ketal 199.8 g (99.2% purity; 83.8% yield)

Fraction 3: cis-methyl-3-oxo-2-pentylcyclopentanacetate ethyleneglycol ketal 30.9 g (98.5% purity; 12.9% yield)

1.3. Ketol Hydrolysis

Into a flask 1 L, equipped with a mechanical stirrer and a reflux condenser, 52 g of aq. citric acid (25%), 86 g of cis-methyl-3-oxo-2-pentylcyclopentanacetate ethyleneglycol ketal (98.5% purity and cis:trans ratio of 93:7) and 9 g of heptane were added. The biphasic mixture was vigorously stirred at 80° C. over 4 h. Then the stirring was stopped and the phases were allowed to separate. The water phase was discharged and the organic phase was washed twice with water. The organic phase was evaporated to dryness and after cooling down, 73 g of crude methyl-3-oxo-2-pentylcyclopentanacetate with a cis:trans ratio of 88:12 was obtained.

The crude methyl-3-oxo-2-pentylcyclopentanacetate can be further purified by flash distillation at T_{vap} 108° C./1 mbar. By further flash distillation of the crude methyl-3-oxo-2-pentylcyclopentanacetate, 70.8 g of pure methyl-3-oxo-2-pentylcyclopentanacetate with a cis:trans ratio of 85:15 and 97% yield is obtained.

Example 2

Catalyst Screening for the Ketol Formation

A catalyst screening for the ketol formation of methyl-3-oxo-2-pentylcyclopentanacetate has been carried out using the general process parameters as following:

In a reaction flask were added methyl-3-oxo-2-pentylcyclopentanacetate (1 eq.), toluene 200%, ethylene glycol (1.5 eq.) and catalyst 0.1-5 mol %. The mixture was stirred at reflux over 6 h. Water was continuously removed using a Dean Stark equipment.

The yield and selectivity was determined by using GC (db-1 column (10 mx0.1 mm) with a temperature gradient starting at 100° C. for 0.5 min, then moving at 25° C./min to 150° C. and then 80° C./min to 250° C.; trans isomer retention time: 3.22 min and cis isomer retention time: 3.26 min) from the crude reaction mixture.

The results with various catalysts are shown in Table 1.

TABLE 1

15 Process of the Invention with Various Compounds of Formula (I)

3.1 Ketol Formation and Distillation—General Protocol

20 Into a flask, equipped with a mechanical stirrer, a reflux condenser and a Dean Stark apparatus, 1 equivalent of compound of formula (I), 150% w/w of heptane, 2 equivalents of ethylene glycol and 0.015 equivalents of potassium hydrogen sulfate were added. The mixture was brought to reflux during 10 h while removing water continuously by azeotropic distillation. The reaction was cooled to 50° C., neutralized by aqueous potassium carbonate then washed with water. After evaporation to dryness, the corresponding ketal was obtained. Each crude material was subjected to fractional distillation as reported in example 1.2. in order to get pure trans and pure cis ketal isomer. All data are given in the followings

With Compound of Formula (I) being
35 Methyl-3-oxo-2-hexylcyclopentanacetate

The crude material obtained consisted of 9% methyl-3-oxo-2-hexylcyclopentanacetate, 75% trans-methyl-3-oxo-2-hexylcyclopentanacetate ethyleneglycol ketal and 11% cis-methyl-3-oxo-2-hexylcyclopentanacetate ethyleneglycol ketal.

trans-methyl-3-oxo-2-hexylcyclopentanacetate ethyleneglycol ketal (98% purity)

45 H₁-NMR (CD₂Cl₂, 600 MHz) δ 0.88 (t, J=6.9 Hz, 3H), 1.1-1.4 (series of m, 10H), 1.5-1.6 (series of m, 2H), 1.6-1.8 (m, 2H), 1.9 (m, 1H), 2.0 (m, 1H), 2.2 (dd, J₁=9.4 Hz, J₂=14.6 Hz, 1H), 2.5 (dd, J₁=5.0 Hz, J₂=14.6 Hz, 1H) 3.6 (s, 3H), 3.8-3.9 (m, 4H).

50 ¹³C-NMR (CD₂Cl₂, 125 MHz) δ 14.3 (q), 23.1 (t), 28.4 (t), 28.4 (t), 29.4 (t), 30.2 (d), 32.2 (t), 35.5 (t), 40.1 (d), 40.5 (t), 51.2 (d), 51.6 (q), 64.4 (t), 65.0 (t), 118.3 (s), 173.6 (s).

55 cis-methyl-3-oxo-2-hexylcyclopentanacetate ethyleneglycol ketal (96% purity)

H₁-NMR (CD₂Cl₂, 600 MHz) δ 0.88 (t, J=6.9 Hz, 3H), 1.1-1.4 (series of m, 10H), 1.5-1.6 (series of m, 2H), 1.6-1.8 (m, 2H), 1.9 (m, 1H), 2.0 (m, 1H), 2.2 (dd, J₁=9.4 Hz, J₂=14.6 Hz, 1H), 2.4 (dd, J₁=4 Hz, J₂=15.5 Hz, 1H) 3.6 (s, 3H), 3.8-4.4 (m, 4H).

60 ¹³C-NMR (CD₂Cl₂, 125 MHz) δ 14.3 (q), 23.1 (t), 24.4 (t), 27.6 (t), 28.6 (t), 30.2 (t), 32.2 (t), 34.8 (t), 35.3 (t), 36.2 (d), 49.5 (d), 51.6 (q), 64.5 (t), 65.2 (t), 118.1 (s), 174.3 (s).

With Compound of Formula (I) being
65 Methyl-3-oxo-2-butylcyclopentanacetate

The crude material obtained consisted of 4% methyl-3-oxo-2-butylcyclopentanacetate, 87% trans-methyl-3-oxo-2-

butylcyclopentanacetate ethyleneglycol ketal and 8% cis-methyl-3-oxo-2-butylcyclopentanacetate ethyleneglycol ketal.

trans-methyl-3-oxo-2-butylcyclopentanacetate ethyleneglycol ketal (99% purity)

H₁-NMR (CDCl₃, 600 MHz) δ 0.89 (t, J=7.0 Hz, 3H), 1.1-1.4 (series of m, 6H), 1.5-1.6 (m, 2H), 1.6-1.8 (m, 2H), 1.9 (m, 1H), 2.1 (m, 1H), 2.2 (dd, J₁=9.8 Hz, J₂=15.0 Hz, 1H), 2.5 (dd, J₁=4.9 Hz, J₂=15.0 Hz, 1H) 3.6 (s, 3H), 3.8-4.0 (m, 4H).

13C-NMR (CDCl₃, 125 MHz) δ 14.1 (q), 23.1 (t), 28.0 (t), 28.8 (t), 30.3 (t), 35.2 (t), 38.6 (d), 40.3 (t), 50.9 (d), 51.4 (q), 64.0 (t), 64.6 (t), 118.0 (s), 173.5 (s).

cis-methyl-3-oxo-2-butylcyclopentanacetate ethyleneglycol ketal (97% purity)

H₁-NMR (CDCl₃, 600 MHz) δ 0.89 (t, J=6.9 Hz, 3H), 1.1-1.6 (series of m, 7H), 1.6-1.9 (m, 3H), 2.0 (m, 1H), 2.2 (m, 1H), 2.4 (dd, J₁=4 Hz, J₂=15.5 Hz, 1H), 2.5 (m, 1H), 3.6 (s, 3H), 3.8-4.0 (m, 4H).

13C-NMR (CDCl₃, 125 MHz) δ 14.1 (q), 23.1 (t), 23.6 (t), 27.2 (t), 30.5 (t), 34.4 (t), 35.1 (t), 35.8 (d), 49.2 (d), 51.4 (q), 64.1 (t), 64.8 (t), 117.8 (s), 174.3 (s).

With Compound of Formula (I) Being
3-Methyl-2-pentylcyclopentan-1-one

The crude material obtained consisted of 7% 3-methyl-2-pentylcyclopentan-1-one, 81% trans-7-methyl-6-pentyl-1,4-dioxaspiro[4.4]nonane and 11% cis-7-methyl-6-pentyl-1,4-dioxaspiro[4.4]nonane.

trans-7-methyl-6-pentyl-1,4-dioxaspiro[4.4]nonane (99% purity)

H₁-NMR (CD₂Cl₂, 600 MHz) δ 0.88 (t, J=6.9 Hz, 3H), 1.0 (d, J=6.2 Hz, 3H), 1.1-1.4 (series of m, 8H), 1.5-2.1 (series of m, 6H), 3.7-4.0 (m, 4H).

13C-NMR (CD₂Cl₂, 125 MHz) δ 14.3 (q), 20.8 (q), 23.0 (t), 28.3 (t), 29.0 (t), 31.0 (t), 32.9 (t), 36.2 (t), 38.7 (d), 56.8 (d), 64.6 (t), 64.9 (t), 119.0 (s).

cis-7-methyl-6-pentyl-1,4-dioxaspiro[4.4]nonane (99% purity)

H₁-NMR (CD₂Cl₂, 600 MHz) δ 0.87 (t, J=6.9 Hz, 3H), 1.1 (d, J=6.5 Hz, 3H), 1.1-2.3 (series of m, 14H), 3.7-4.0 (m, 4H).

13C-NMR (CD₂Cl₂, 125 MHz) δ 14.2 (q), 19.9 (q), 22.9 (t), 27.0 (t), 28.2 (t), 30.0 (t), 32.6 (t), 37.4 (d), 38.4 (t), 53.5 (d), 64.2 (t), 65.2 (t), 118.6 (s).

With Compound of Formula (I) Being
Ethyl-3-oxo-2-pentylcyclopentanacetate

The crude material obtained consisted of 7% ethyl-3-oxo-2-pentylcyclopentanacetate, 81% trans-ethyl-3-oxo-2-pentylcyclopentanacetate ethyleneglycol ketal and 11% cis-ethyl-3-oxo-2-pentylcyclopentanacetate ethyleneglycol ketal.

trans-ethyl-3-oxo-2-pentylcyclopentanacetate ethyleneglycol ketal (99% purity)

H₁-NMR (CD₂Cl₂, 600 MHz) δ 0.88 (t, J=6.9 Hz, 3H), 1.2 (t, J=6.9 Hz, 3H), 1.2-1.4 (series of m, 8H), 1.5 (m, 2H), 1.6-1.8 (m, 2H), 1.9 (m, 1H), 2.0 (m, 1H), 2.2 (m, 1H), 2.5 (dd, J₁=5.0 Hz, J₂=14.6 Hz, 1H) 3.7-3.9 (m, 4H), 4.0 (q, J=7.1 Hz, 2H).

13C-NMR (CD₂Cl₂, 125 MHz) δ 14.3 (q), 14.5 (q), 23.0 (t), 28.1 (t), 28.3 (t), 29.3 (t), 32.8 (t), 35.5 (t), 40.1 (d), 40.8 (t), 51.2 (d), 60.4 (t), 64.3 (t), 64.9 (t), 118.3 (s), 173.1 (s).

cis-ethyl-3-oxo-2-pentylcyclopentanacetate ethyleneglycol ketal (95% purity)

H₁-NMR (CD₂Cl₂, 600 MHz) δ 0.88 (t, J=6.9 Hz, 3H), 1.2 (t, J=6.9 Hz, 3H), 1.2-1.4 (series of m, 8H), 1.5 (m, 1H), 1.6-1.8 (m, 3H), 1.9 (m, 1H), 2.2 (m, 1H), 2.3 (dd, J₁=5.0 Hz, J₂=14.6 Hz, 1H), 2.6 (m, 1H), 3.7-3.9 (m, 4H), 4.1 (q, J=7.1 Hz, 2H).

13C-NMR (CD₂Cl₂, 125 MHz) δ 14.3 (q), 14.5 (q), 23.0 (t), 24.3 (t), 26.8 (t), 27.5 (t), 30.2 (t), 35.0 (t), 35.2 (t), 36.2 (d), 49.4 (d), 60.4 (t), 64.5 (t), 65.2 (t), 118.2 (s), 173.8 (s).

With Compound of Formula (I) Being Methyl (Z)-2-(3-oxo-2-(pent-2-en-1-yl)cyclopentyl)acetate

The crude material obtained consisted of 7% methyl (Z)-2-(3-oxo-2-(pent-2-en-1-yl)cyclopentyl)acetate, 77% trans-methyl (Z)-2-(3-oxo-2-(pent-2-en-1-yl)cyclopentyl)acetate ethyleneglycol ketal and 8% cis-methyl (Z)-2-(3-oxo-2-(pent-2-en-1-yl)cyclopentyl)acetate ethyleneglycol ketal.

trans-methyl (Z)-2-(3-oxo-2-(pent-2-en-1-yl)cyclopentyl)acetate ethyleneglycol ketal

H₁-NMR (CD₂Cl₂, 600 MHz) δ 0.95 (t, J=7.5 Hz, 3H), 1.27 (m, 1H), 1.6-1.94 (series of m, 4H), 2.06 (m, 4H), 2.2 (m, 2H), 2.56 (dd, J=15 Hz, J=4.8 Hz, 1H), 3.6 (s, 3H), 3.86 (m, 4H), 5.34 (m, 2H).

13C-NMR (CD₂Cl₂, 125 MHz) δ 14.3 (q), 20.9 (t), 26.8 (t), 28.6 (t), 35.5 (t), 39.8 (d), 40.3 (t), 51.5 (q), 51.6 (d), 64.6 (t), 65.0 (t), 118.1 (s), 128.2 (d), 132.1 (d), 173.5 (s).

cis-methyl (Z)-2-(3-oxo-2-(pent-2-en-1-yl)cyclopentyl)acetate ethyleneglycol ketal

H₁-NMR (CD₂Cl₂, 600 MHz) δ 0.95 (t, J=7.5 Hz, 3H), 1.4 (m, 1H), 1.5 (sb, 2H), 1.7-1.9 (series of m, 2H), 1.9-2.1 (m, 4H), 2.2 (m, 1H), 2.4 (dd, J=15.0 Hz, J=4.8 Hz, 1H), 2.5 (m, 1H), 3.6 (s, 3H), 3.86 (m, 4H), 5.34 (m, 2H).

13C-NMR (CD₂Cl₂, 125 MHz) δ 14.3 (q), 21.1 (t), 22.4 (t), 27.8 (t), 35.1 (t), 35.1 (t), 36.3 (d), 49.6 (d), 51.6 (q), 64.6 (t), 65.2 (t), 118.1 (s), 128.2 (d), 132.3 (d), 174.2 (s).

With Compound of Formula (I) Being Ethyl (Z)-2-(3-oxo-2-(pent-2-en-1-yl)cyclopentyl)acetate

The crude material obtained consisted of 10% ethyl (Z)-2-(3-oxo-2-(pent-2-en-1-yl)cyclopentyl)acetate, 80% trans-ethyl (Z)-2-(3-oxo-2-(pent-2-en-1-yl)cyclopentyl)acetate ethyleneglycol ketal and 8% cis-ethyl (Z)-2-(3-oxo-2-(pent-2-en-1-yl)cyclopentyl)acetate ethyleneglycol ketal.

trans-methyl (Z)-2-(3-oxo-2-(pent-2-en-1-yl)cyclopentyl)acetate ethyleneglycol ketal

H₁-NMR (CD₂Cl₂, 600 MHz) δ 0.95 (t, J=7.4 Hz, 3H), 1.22 (t, J=7.1 Hz, 3H), 1.27 (m, 1H), 1.6-1.8 (series of m, 3H), 1.9 (m, 1H), 2.06 (m, 4H), 2.11-2.26 (series of m, 2H), 2.55 (dd, J=15.0 Hz, J=4.5 Hz, 1H), 3.85 (m, 4H), 4.08 (q, J=7.1 Hz, 2H), 5.36 (m, 2H).

13C-NMR (CD₂Cl₂, 125 MHz) δ 14.4 (q), 14.5 (q), 20.9 (t), 26.8 (t), 28.3 (t), 35.5 (t), 39.9 (d), 40.6 (t), 51.6 (d), 60.4 (t), 64.5 (t), 65.0 (t), 118.0 (s), 128.3 (d), 132.3 (d), 173.0 (s).

cis-methyl (Z)-2-(3-oxo-2-(pent-2-en-1-yl)cyclopentyl)acetate ethyleneglycol ketal

H₁-NMR (CD₂Cl₂, 600 MHz) δ 0.95 (t, J=7.4 Hz, 3H), 1.22 (t, J=7.1 Hz, 3H), 1.27 (m, 1H), 1.6-2.0 (series of m, 4H), 2.0-2.2 (m, 4H), 2.2-2.4 (series of m, 2H), 2.66 (m, 1H), 3.82 (m, 4H), 4.1 (q, J=7.1 Hz, 2H), 5.36 (m, 2H).

13C-NMR (CD₂Cl₂, 125 MHz) δ 14.3 (q), 14.4 (q), 21.0 (t), 25.8 (t), 27.4 (t), 27.6 (t), 38.0 (t), 38.5 (d), 49.6 (d), 60.7 (t), 64.1 (t), 65.3 (t), 118.0 (s), 128.2 (d), 132.2 (d), 173.6 (s).

3.2 Hydrolysis—General Protocol

Into a flask 1 L, equipped with a mechanical stirrer and a reflux condenser, 60% w/w of Citric acid 25% in water, 1

11

equivalent of pure Cis ketal obtained in step 3.1 and 10% w/w of Heptane were added. The biphasic mixture were vigorously stirred at 80° C. over 4 h. Then the stirring was stopped and the phases were allowed to separate. The water phase was discharged and the organic phase was washed twice with water. The organic phase was evaporated to dryness and after cooling down, the crude was obtained.

The crudes were further purified by flash distillation at T_{vap} 108/1 mbar given:

Cis-methyl-3-oxo-2-hexylcyclopentanacetate

Cis-methyl-3-oxo-2-hexylcyclopentanacetate was obtained with a cis:trans ratio of 95:5 and 97% yield (purity 99%).

H1-NMR (CDCl₃, 400 MHz) δ 0.88 (t, J=6.9 Hz, 3H), 1.1-1.5 (sb, 10H), 1.6 (m, 1H), 1.8 (m, 1H), 1.9-2.2 (series of m, 2H), 2.2 (m, 3H), 2.4 (m, 1H), 3.7 (s, 3H). 13C-NMR (CDCl₃, 90 MHz) δ 14.1 (q), 22.6 (t), 24.7 (t), 25.7 (t), 27.4 (t) 29.4 (t), 31.6 (t), 33.7 (t), 35.2 (t), 35.7 (d), 51.7 (q), 52.7 (d), 173 (s), 219.3 (s).

Cis-methyl-3-oxo-2-butylcyclopentanacetate

Cis-methyl-3-oxo-2-butylcyclopentanacetate was obtained with a cis:trans ratio of 94:6 and 97% yield (purity 99%).

H1-NMR (CDCl₃, 600 MHz) δ 0.89 (t, J=7.0 Hz, 3H), 1.1-1.7 (series of m, 6H), 1.8 (m, 1H), 2.0-2.5 (series of m, 6H), 2.8 (m, 1H), 3.7 (s, 3H). 13C-NMR (CDCl₃, 90 MHz) δ 13.9 (q), 22.7 (t), 24.4 (t), 25.6 (t), 29.6 (t), 33.7 (t), 35.1 (t), 35.7 (d), 51.7 (q), 52.7 (d), 173.0 (s), 219.2 (s).

Cis-3-methyl-2-pentylcyclopentan-1-one

Cis-3-methyl-2-pentylcyclopentan-1-one was obtained with a cis:trans ratio of 98:2 and 99% yield (purity 99%).

NMR As reported in Fink, Michael J.; Chem Cat Chem (2013), 5(3), 724-727

Cis-ethyl-3-oxo-2-pentylcyclopentanacetate

Cis-ethyl-3-oxo-2-pentylcyclopentanacetate was obtained with a cis:trans ratio of 96:4 and 97% yield (purity 99%).

H1-NMR (CDCl₃, 400 MHz) δ 0.88 (t, J=6.9 Hz, 3H), 1.3 (t, J=7.1 Hz, 3H+m, 7H), 1.6 (m, 1H), 1.8 (m, 1H), 1.9-2.2 (series of m, 2H), 2.2 (m, 3H), 2.4 (dd, J₁=5.9 Hz, J₂=15.0 Hz, 1H), 2.8 (m, 1H), 4.1 (q, 2H). 13C-NMR (CDCl₃, 90 MHz) δ 14.1 (q), 14.2 (q), 24.7 (t), 25.6 (t), 27.4 (t), 29.4 (t) 31.6 (t) 34.0 (t), 35.2 (t), 35.7 (d), 52.7 (d), 60.6 (t), 172.6 (s), 219.4 (s)

Cis-methyl (Z)-2-(3-oxo-2-(pent-2-en-1-yl)cyclopentyl)acetate

Cis-methyl (Z)-2-(3-oxo-2-(pent-2-en-1-yl)cyclopentyl)acetate was obtained with a cis:trans ratio of 93:7 and 96% yield (purity 97%).

H1-NMR (CDCl₃, 400 MHz) δ 0.9-1.0 (t, J=7.5 Hz, 3H+m, 2H), 1.8 (m, 1H), 2.0-2.5 (series of m, 8H), 2.85 (m, 1H), 3.7 (s, 3H), 5.34 (m, 1H), 5.45 (m, 1H). 13C-NMR (CDCl₃, 100 MHz) δ 14.1 (q), 20.7 (t), 23.0 (t), 25.7 (t), 33.7 (t), 35.3 (t), 35.6 (d), 51.7 (q), 52.7 (d), 125.5 (d), 133.5 (d), 172.9 (s), 218.8 (s).

12

Cis-ethyl (Z)-2-(3-oxo-2-(pent-2-en-1-yl)cyclopentyl)acetate

Cis-ethyl (Z)-2-(3-oxo-2-(pent-2-en-1-yl)cyclopentyl)acetate was obtained with a cis:trans ratio of 93:7 and 96% yield (purity 97%).

H1-NMR (CDCl₃, 600 MHz) δ 0.96 (t, J=7.5 Hz, 3H), 1.27 (t, J=7.1 Hz, 3H+m, 2H), 1.5 (m, 1H), 1.8 (m, 1H), 2.0-2.5 (series of m, 7H), 2.8 (m, 1H), 4.2 (q, J=7.1 Hz, 2H), 5.2 (m, 1H) 5.3 (m, 1H). 13C-NMR (CDCl₃, 90 MHz) δ 14.0 (q), 14.2 (q), 20.7 (t), 23.0 (t), 25.6 (t), 34.0 (t), 35.4 (t), 35.6 (d), 52.7 (d), 60.6 (t), 125.5 (d), 133.5 (d), 172.5 (s), 219.0 (s).

Example 4

Diol Screening for the Ketal Formation

A diol screening for the ketal formation of methyl-3-oxo-2-pentylcyclopentanacetate has been carried out using the general process parameters as following:

In a reaction flask were added methyl-3-oxo-2-pentylcyclopentanacetate (1 eq.), toluene 200%, diol (1.5 eq.) and catalyst 0.1-5 mol %. The mixture was stirred at reflux over 6 h. Water was continuously removed using a Dean Stark equipment.

The yield and selectivity was determined by using GC (db-1 column (10 m×0.1 mm) with a temperature gradient starting at 100° C. for 0.5 min, then moving at 25° C./min to 150° C. and then 80° C./min to 250° C.) from the crude reaction mixture.

The results with various diols are shown in Table 2.

TABLE 2

Diol	Ketal formation with various diols		
	methyl-3-oxo-2-pentylcyclopentanacetate	trans-methyl-3-oxo-2-pentylcyclopentanacetate diol ketal	cis-methyl-3-oxo-2-pentylcyclopentanacetate diol ketal
Ethylene glycol	18	69	10.5
1,3-propanediol	22.4	61.6	9.4
2,2-dimethyl-1,3-propanediol	6	78	12.6

The mixture resulting from step a) as displayed in the above table can be treated exactly the same way as described in Example 1.2. and 1.3. Namely, the separation of trans:cis ketal isomers by distillation followed by selective hydrolysis of cis or trans ketal isomer affording enriched to pure cis methyl-3-oxo-2-pentylcyclopentanacetate.

The invention claimed is:

1. A process for the preparation of a mixture of compounds of formula

13

having a weight ratio of the cis-diastereomers to trans-diastereomers higher than 1:1, wherein R₁ represents a C₁₋₈ alkyl group, a C₂₋₈ alkenyl group or a C₂₋₈ alkynyl group, each optionally substituted with one or two of a C₁₋₄ alkyl alkoxy ether group and/or C₁₋₄ alkyl carboxylester group, and R₂ represents a C₁₋₆ alkyl group, a C₂₋₆ alkenyl group or a C₂₋₆ alkynyl group, each optionally substituted with an C₁₋₄ alkyl alkoxy ether group, a carboxylic acid group or a C₁₋₄ alkyl carboxylester group, by subjecting a mixture of compounds of formula

(I)

having a weight ratio of the cis-diastereomers to trans-diastereomers equal or lower than 1:1,

wherein R₁ and R₂ have the same meaning as indicated above,

to the steps comprising (a) ketal formation, (b) separating the trans-diastereomers and cis-diastereomers and (c) hydrolyzing the ketal of the cis-diastereomers.

2. The process according to claim 1, wherein R₁ represents a linear C₃₋₇ alkyl group or a linear C₃₋₇ alkenyl group or a linear C₃₋₇ alkynyl group.

3. The process according to claim 1, wherein R₂ represents a C₁₋₃ alkyl group optionally substituted with a C₁₋₃ alkyl carboxylester group.

4. The process according to claim 1, wherein the compound of formula (I) is methyl-3-oxo-2-pentylcyclopentanacetate, methyl-3-oxo-2-(2-pentenyl)-1-cyclopentaneacetate or (Z)-methyl-3-oxo-2-(2-pentenyl)-1-cyclopentaneacetate.

5. The process according to claim 1, wherein step (b) is carried out by distillation.

6. The process according to claim 1, wherein step (a) is carried out in the presence of an acid.

7. The process according to claim 1, wherein step (a) is carried out in a hydrocarbon solvent.

8. The process according to claim 1, wherein step (a) is carried out in the presence of a diol of formula HO—C(R₄)H—(C(R₄)₂)_n—H(R₄)C—OH wherein n is an integer from 0 to 3 and R₄, each independently, is a hydrogen or C₁₋₃ alkyl group.

9. The process according to claim 1, wherein step (a) is carried out in the presence of ethylene glycol, 1,3-propane-

diol, 2,3-butanediol, 1,2-propanediol, 2,2-dimethyl-1,3-propanediol, 1,2-butanediol, or 2-methyl-1,3-propanediol.

10. The process according to claim 1, wherein step (c) is carried out in the presence of an acid.

11. The process according to claim 1, wherein step (a) is carried out in the presence of H₂SO₄, pyridium tosylate, MHSO₄, wherein M is an alkaline metal, Al₂(SO₄)₃, heterogeneous solid acid, or alkyl or aryl sulfonic acid.

12. The process according to claim 1, wherein step (a) is carried out in the presence of KHSO₄.

13. The process according to claim 1, wherein step (a) is carried out in toluene or heptane.

14. The process according to claim 1, wherein step (a) is carried out in the presence of ethylene glycol.

15. The process according to claim 1, wherein step (c) is carried out in the presence of citric acid.

16. The process according to claim 1, wherein the weight ratio of the cis-diastereomers to the trans-diastereomers of the mixture of compounds of formula (I) is less than 40:60.

17. The process according to claim 1, wherein the weight ratio of the cis-diastereomers to the trans-diastereomers of the prepared mixture after separating the trans-diastereomers and cis-diastereomers is at least 60:40.

18. The process according to claim 1, wherein the ketal formation comprises formation of a ketal compound according to formula

(II)

wherein R₁ represents a C₁₋₈ alkyl group, a C₂₋₈ alkenyl group or a C₂₋₈ alkynyl group, each optionally substituted with one or two of a C₁₋₄ alkyl alkoxy ether group and/or C₁₋₄ alkyl carboxylester group, and R₂ represents a C₁₋₆ alkyl group, a C₂₋₆ alkenyl group or a C₂₋₆ alkynyl group, each optionally substituted with an C₁₋₄ alkyl alkoxy ether group, a carboxylic acid group or a C₁₋₄ alkyl carboxylester group, and

R₃ represent, each independently, a C₂₋₃ alkyl group or, when two R₃ taken together, is a bivalent group —C(R₄)H—(C(R₄)₂)_n—H(R₄)C— wherein n is an integer from 0 to 3 and R₄, each independently, is a hydrogen or C₁₋₃ alkyl group, with the proviso that at least one R₄ is a linear or branched C₁₋₃ alkyl group when n is 0.
